United States Patent Office.

ROBERT WALLACE, OF WALLINGFORD, ASSIGNOR TO THE MERIDEN BRITANNIA COMPANY, OF MERIDEN, CONNECTICUT.

Design No. 4,070, dated May 24, 1870.

DESIGN FOR SUGAR-TONGS.

The Schedule referred to in these Letters Patent and making part of the same.

To all whom it may concern:

Be it known that I, ROBERT WALLACE, of Wallingford, in the county of New Haven and State of Connecticut, have invented a new Design for Sugar-Tongs; and I do hereby declare the following, when taken in connection with the accompanying drawings and the letters of reference marked thereon, to be a full, clear, and exact description of the same, and which said drawings constitute part of this specification, and represent in—

Figure 1, a side view, and in

Figure 2, the bow or spring extended.

This invention relates to a design for the spring portion of sugar-tongs, and tongs for similar purposes, the object being to make this part of the article ornamental; and

My invention consists in the peculiar form or configuration of the edges of the spring, as more fully hereafter explained.

A is the handle of one part, and
B, the handle of the other part of the tongs.
C is the spring which connects the two parts.

Starting from the ends of the handle the spring is somewhat narrower than the handle, and straight for a short distance, then of ogee form, meeting with an ornamental or irregular edge at the center, as fully shown in fig. 2, of the accompanying drawings.

The surface of the spring may be ornamented in any desirable style.

I claim as my invention—

The design for the spring portion of sugar-tongs, as herein illustrated and described.

ROBERT WALLACE.
